UNITED STATES PATENT OFFICE.

DAVID KIRKWOOD, OF BOSTON, MASSACHUSETTS.

BREECH-LOADING FIRE-ARM.

SPECIFICATION forming part of Letters Patent No. 233,773, dated October 26, 1880.

Application filed August 11, 1880. (No model.)

To all whom it may concern:

Be it known that I, DAVID KIRKWOOD, a citizen of the United States, residing at Boston, in the county of Suffolk and State of Massachusetts, have invented certain Improvements 5 in Self-Cocking Breech-Loading Fire-Arms, of which the following is a full, clear, and exact description, reference being had to the accompanying drawings, forming part of this specification, in explaining its nature.

Figure 1 is a plan of a portion of a double-barreled gun comprising the breech and adjacent parts. Fig. 2 is a view, part in side elevation and part in section, with the side plate 15 of the breech removed, illustrating the construction of my invention. Fig. 3 is a plan view of a portion of the mechanism hereinafter described. Fig. 4 is a detail. Fig. 5 is a cross-section on the line $x-x$ of Fig. 2; Fig. 6, 20 a detail view, representing the method of attaching the hammer to the lug on the breech end of the barrel. Fig. 7 represents the hammer and sear in elevation. Fig. 8 represents, in elevation, a modification of the method described of operating the locking-bar.

My invention relates to the class of breech-loading guns—either single or double barrel—known as the “self-cocking” breech-loading guns, in which the hammer is automatically 30 cocked upon the movement of the barrel to expose the breech, and the trigger locked to prevent the accidental discharge of the gun; and it is an improvement thereon, in that the construction of parts for effecting the self-cocking 35 and for locking the trigger is simpler, less likely to get out of order, cheaper, and more easily worked than the construction now employed, as is hereinafter fully described and claimed.

40 A is the barrel or barrels. It or they are hinged or pivoted at a to the breech-piece B, to tilt downwardly at the muzzle, and upwardly at the breech.

C is the hammer. It is pivoted at c to the 45 breech-piece, and its arm c' bears at its end a horizontal pin or spur, c^2 , that projects upon the shoulder c^3 , formed on the locking-lug c^4 , attached to the part c^5 of the barrel. This shoulder is formed by cutting a recess in the

side of the lug, or by attaching a flat piece to 50 its bottom, or in any other desirable way.

The hammer bears, near its striking end, a tumbler-catch, c^6 , which is adapted to engage with the sear-nose e on the sear E.

The trigger and trigger-spring may be of 55 ordinary construction, or the sear may be in one piece with the trigger.

F is the hammer-spring. The connection between its end f and the hammer is by means of a toggle-link, f' , which enters a tapering 60 slot, f^2 , in the hammer at the rear of the pivot c . The end of the slot should extend a trifle beyond a horizontal line drawn from the pivot, and when uncocked the end of the toggle-link should not extend quite to this horizontal 65 line, in order that provision for the easy play of the toggle may be provided. Any suitable spring for giving motion to the hammer may be used in lieu of this; but I prefer a construction that employs a swivel, toggle, or 70 other loose connection between the end of the spring and the hammer.

The operation of this part of my invention is as follows: Upon unlocking the barrel it is turned downwardly at the muzzle, thereby lifting the breech and lug c^4 , causing the hammer C to be moved on its pivot sufficiently to enable the tumbler-catch to engage the sear-nose. The connection between the arm c' of the hammer and the lug is such that sufficient play is 75 allowed of the pin on the shoulder c^3 while the breech is being moved upwardly, and to ease this movement the shoulder may be made higher at its outer end, as represented in Fig. 2, in order that the surface on which the pin 80 bears may be somewhat inclined when in a horizontal position. Upon the downward movement of the breech the shoulder c^3 is disengaged from the pin or spur, and the hammer is tripped upon releasing the trigger in the 85 usual way. For a double-barreled gun these parts are duplicated.

The device for locking the trigger before the cocking of the hammer consists in the sliding bar G, one end of which projects into a recess, 95 g , in the side of the stud g' , which is operated by the top lever, g^2 , in retracting the bolt H from the locking-lugs. This recess is of such

a shape that upon the partial revolution of the stud the shoulder g^3 , which forms one side thereof, acts to move the bar horizontally, thereby causing it to move the locking-bar G' sufficiently to shut upon the trigger g^4 or sear.

5 In lieu of the recess in the stud, the stud may have an arm or pin projecting therefrom, as shown in Figs. 2 and 3, for effecting the movement of the sliding bar. The bar has a slot, g^5 , and a screw-stud, g^6 , which passes through the slot g^5 in the sliding bar, fastens it to the strap portion of the breech-piece, and allows the bar to slide a limited extent.

10 There is a loose connection between the locking-bar and sliding bar. The locking-bar is attached to the pivot g^7 , which bears at its outer end the side lever, g^8 . The trigger g^4 may have a notch, h , over which the locking-bar G' is moved when tripped, thereby allowing the 15 trigger to be moved upwardly, or it may be moved beyond the end of the trigger. In Fig. 4 I show a modification in construction, whereby the locking-bar is adapted to lock the sear instead of the trigger.

20 25 In case the friction of the parts is not sufficient to maintain the locking-bar in position on the trigger or sear after the top lever has moved back to its original position, a spring, g^9 , of sufficient strength to maintain it in that 30 position, but not sufficiently strong to return it to that position when the side lever, g^8 , is moved to disengage the locking-bar, may be used, or the side lever, g^8 , may be made to bear against the side plate with sufficient stress to 35 keep the locking-bar in position.

40 The operation of this part of my invention is as follows: Upon moving the top lever to withdraw the locking-bolt the bar G is moved sufficiently to throw the locking-bar G' into a 45 position to lock the trigger or sear, and the locking-bar remains in that position after the top lever has returned to its original position and until it is moved therefrom by the side lever, g^8 . The simplicity of this construction and its advantages are obvious.

In order to engage the barrel with the hammer when it is down or uncocked, the construction of the arm c' of the hammer, its pin, and the shoulder on the lug may be such that the shoulder may engage with the pin during the 50 downward movement of the barrel, in which event the arm c' must be made thinner, so as to become a spring and yield laterally in relation to the shoulder to allow it to pass by the pin on the hammer-arm; but I do not confine myself to this construction.

55 Of course I do not confine myself to the described connection of the hammer-arm c' with the lug c^4 , but may connect it by a loose joint having the characteristics of the joint described to any part of the breech of the gun that shall have a movement of any description in relation to the hammer to move it sufficiently to engage with the sear-nose; and for the purpose of operating the locking-bar G' , I do not 60 confine myself to the mechanism shown, but may use any suitable mechanism employed for locking the barrel to the stock, which has to be moved by hand in unlocking the barrel, so that the barrel may be unlocked from the 65 breech-piece and the locking-bar operated by one movement of lever, push-knob, or button.

Having thus fully described my invention, I claim and desire to secure by Letters Patent of the United States—

70 75 1. In a break-down self-cocking gun, the hammer-arm c' , in combination with the locking-lug c^4 , provided with a shoulder, c^3 , whereby the locking-lug acts directly on the hammer-arm, substantially as set forth.

80 85 2. In a break-down self-cocking gun, a pivoted trigger-locking device, G' , in combination with and operated by the barrel-locking lever g^2 and sliding bar G , substantially as described.

Witness my hand this 7th day of August, 1880.

DAVID KIRKWOOD.
